Fig. 5

Fig. 6

FIG. 1 is a side elevational view of the push-button spin casting reel, showing my new design.

FIG. 2 is a side elevational view showing the reel from the other side.

FIG. 3 is a top view of the reel.

FIG. 4 is a bottom view of the reel.

FIG. 5 is an elevational view taken from the front, and

FIG. 6 is an elevational view taken from the rear.

FIGS. 7 and 8 are respectively three-quarter perspective views of the right and left sides of the reel as viewed substantially from the top thereof.

The essential features of my design reside in the parts shown in solid lines.

I claim:

The ornamental design for a push-button spin casting reel, substantially as shown and described.
